UNITED STATES PATENT OFFICE.

ARNOLD WACHE, OF BRESLAU, GERMANY.

CARVING-MACHINE.

SPECIFICATION forming part of Letters Patent No. 602,887, dated April 26, 1898.

Application filed August 28, 1894. Serial No. 521,550. (No model.) Patented in France August 17, 1894, No. 240,807; in Germany September 23, 1894, No. 82,220, and in Austria October 23, 1895, No. 45/3,992.

To all whom it may concern:

Be it known that I, ARNOLD WACHE, of 24 Neue Tautentzienstrasse, Breslau, in the Kingdom of Prussia, German Empire, have invented new and useful Improvements in Carving-Machines, (for which I have received a patent in Germany, No. 82,220, bearing date September 23, 1894; in France, No. 240,807, bearing date August 17, 1894, and in Austria, No. 45/3,992, bearing date October 23, 1895,) of which the following is a specification.

My present invention relates to a carving-machine for copying plastical articles. The new machine differs from the constructions hitherto known in that the middle frame carrying the tool-holders and the feeler is not 15 slidable in a longitudinal direction and that the same is jointed to the tool-holders, while in the copying-machines hitherto in use the whole middle frame and the gear-shaft connected with it must be slid in a longitudinal direction. The execution of the present machine is greatly simplified by this modification and its handling is rendered a great deal 20 easier, as the middle frame is only to be arranged rotatorily in its bearings and the possibility of a longitudinal sliding is not provided for. Besides, the jointed connection of the tool-holder with the middle frame permits 25 the copying of one model to the right and left.

This new machine is illustrated by the accompanying drawings, namely:

Figure 1 is a front view of the machine. 35 Fig. 2 is a plan of the same. Fig. 3 is a section. Fig. 4 is a lateral view; and Figs. 5, 6, and 7 represent the principal constituent of the machine, consisting in the details of a movable tool-holder.

40 The whole machine consists of the following two main parts: first, the frame, and, second, the tools, with the parts transferring the movement of the driving-shaft on the same.

45 The frame consists of two lateral frames *a*, fixed to a table *b*. The table-plate *b'* serves to hold the pattern and the materials to be worked. Each of the side frames *a* is provided with a rail *c*. The tool-holders *d* are 50 arranged in a frame *e* and in such a way

movably connected by the connecting-rods *f* with the middle frame *g* as to be turnable out of their central position to the right or left. In Fig. 2 these alterations of position are indicated by dotted lines. The middle frame 55 *g* (see Fig. 6) carries the vertical driving-shafts *g'* in a quantity corresponding with the number of the tool-holders. These vertical shafts carry the pulleys *g''* for the tools. The whole frame *g* is turnably arranged in vertically- 60 adjustable bearings *g⁴* by means of two long pivots *g³*.

The shaft *i*, which carries the pulleys *i'* for the vertical shafts *g'* and which is itself driven by means of the shaft *k* of the gearing *m*, is 65 firmly connected with the frame *g* by some bearing-arms *h*. The connection between the shafts *k* and *i* is movable, so that the tools can be kept in motion with every position of the frame *c*. The bearings *g⁴*, which carry 70 the middle frame *g*, are vertically adjustable in guides *n* and suspended to chains *o* of the counterweight *o'*, which serves to balance the tool-holders, with their frames, and the parts transmitting the movement; but besides this 75 the whole supporting-frame for the middle frame *g*, which principally consists of the guides *n* and the connecting-support *p*, can, by means of the rollers *r*, be horizontally moved on the rails *c*. The frame *g* being 80 thus vertically and horizontally adjustable and being able to swing round its horizontal turning-pivots *g³* it is clear also with regard to the movable connection between the middle frame *g* and the front frame *e* that the 85 tool-holders can be given any position required.

In constructing the whole apparatus I have attached special importance to the circumstance that the dimensions of the tool-holders 90 themselves and of the parts transmitting the movement and effecting the connection for every tool-holder should be exactly the same, so that the movements and alterations of position of all tool-holders must turn out exactly 95 alike.

The tool-holder consists of an outside casting *s* and a rotatory inner part *d*. The interior body carries the shaft *d²*, at the lower end of which the working tool is arranged. 100

It is obvious that in turning the inner part d in the frame s the shaft d^2 , and with it the tool, is compelled to follow the rotation of part d , so that a slanting position is gained. If one has to copy a model in which under-worked places are to be found, the slanting adjustment of all tools is a necessity. In order to attain the uniform adjustment of all tools, the outer frame s is provided with a scale, while the inner slidable part d is provided with a pointer d^4 , by means of which each tool may be adjusted in an equal angle. The machine works in such a way that under the central tool-holder the pattern is placed, while under every other tool-holder a piece of raw material of a size corresponding with the pattern is fixed to the table-plate, whereupon the worker leads the point of the one tool over the contours of the pattern, the other tools being forced to execute exactly the same movements on the material

lying underneath them, thus delivering exact copies of the original to be copied.

Having now described my invention, what I claim, and desire to secure by Letters Patent, is—

In a machine for copying plastic articles, the combination of a middle frame adjustable in vertical and horizontal direction and adapted to swing around its horizontal axis, with a frame pivotally connected to the middle frame, and tool-holders pivotally arranged in the said frame, substantially as and for the purpose set forth.

In witness whereof I have hereunto signed my name in the presence of two subscribing witnesses.

ARNOLD WACHE.
